UNITED STATES PATENT OFFICE.

HARRY RALPH RICARDO, OF LONDON, ENGLAND.

INTERNAL-COMBUSTION ENGINE.

1,296,556.

Specification of Letters Patent.

Patented Mar. 4, 1919.

Application filed August 15, 1917. Serial No. 186,413.

To all whom it may concern:

Be it known that I, HARRY RALPH RICARDO, subject of the King of England, residing at London, in England, have invented certain new and useful Improvements in Internal-Combustion Engines, of which the following is a specification.

This invention relates to internal combustion engines, more especially those of the compound type, that is to say in which the expansion of each explosive charge is carried out in two stages and has for its object to dilute the charge in the high pressure cylinders with an inert gas with a view to economy.

According to this invention some of the exhaust products of combustion, drawn conveniently from the low pressure cylinder, are cooled and then added to the main charge which is diluted thereby. It is then possible to modify the construction of the pump which effects the preliminary compression of the larger part of the main charge so that it is not called upon to do so much work in the precision of gas and in the compression thereof. The exhaust products thus used may be cooled in various ways and either kept separate from the main part of the charge until the latter is in the cylinder, the cooled exhaust products in that case being admitted direct into the high pressure cylinder, or after preliminary cooling these exhaust products may be allowed to mingle with the compressed gas in the chamber in which this gas is cooled before passing to the cylinder.

The details of construction may be modified to suit requirements and the type of compound engine to which the invention is applied.

In the accompanying drawings,

Figure 1 is a part sectional elevation somewhat diagrammatically arranged and showing a construction of compound internal combustion engine with the present invention applied thereto in one form.

Fig. 2 is a sectional elevation through the low pressure cylinder of a similar engine but showing a modified manner of applying the invention thereto.

Like letters indicate like parts throughout the drawings.

Referring to Fig. 1 the engine comprises two high pressure cylinders A and A' and a low pressure cylinder B, the cylinder A' being broken away in order to show the

application of the present invention to the lower pressure cylinder. The engine as regards its main features is constructed and arranged as shown in a copending application Serial Number 186,275. Thus while the products of combustion act respectively on one face of each of the pistons C in the high pressure cylinders A and A' and pass alternately from these cylinders to act on one face of the piston D in the low pressure cylinder B, an annular portion of the opposite face of each of these three pistons acts as a pump to compress gases which are subsequently transferred into the combustion chamber ends of the cylinders A and A'. While the pump face of each piston C compresses combustible mixture in pump chamber A² which subsequently enters a pocket E through conduit E² connecting said pocket and chamber and thence passes through a passage E' into the cylinder A or the cylinder A', the pump face of the piston D compresses air or weak mixture in pump chamber B² which is delivered through the pipe F to a chamber G of suitable construction wherein this air is cooled. The pipe F communicates with a port in the lower end of chamber B² which is not shown because it is behind parts shown in Fig. 1. After cooling the compressed air passes from the chamber G through the pipe H into the cylinders A and A' through the valves J and J' each charge of compressed and cooled air thus serving to supercharge the cylinders A and A'.

At a suitable point in the length of the wall of the low pressure cylinder B is formed one or more ports B' the position of these ports being conveniently such that they will be uncovered when the piston D has performed from half to two-thirds of its outstroke. The ports B' lead into a cooling chamber which is conveniently constructed as shown and comprises a series of tubes K through which the gases can pass from the cylinder B, these tubes being carried at their ends in tube plates K', and surrounded by a casing K² so arranged that water can circulate through it and around and over the pipes K. At the end of this cooling device opposite to that into which the ports B' open there is disposed a non-return valve which controls ports L leading into a pipe L' which communicates with the cooling chamber.

It is to be noted that while the pistons C

- in the cylinders A and A' operate on the four-stroke cycle the piston D in the cylinder B operates on the two-stroke cycle. Thus each outstroke of the piston D is performed under the action of the expanding products of combustion which have passed into the cylinder B, either from the cylinder A or the cylinder A' alternately. At or toward the end of the outstroke of the piston D these products of combustion are permitted to escape to the atmosphere owing to the lifting of the exhaust valve M. When, however, the piston D has performed such part of its outstroke as to uncover the ports B' some of the products of combustion pass under pressure through these ports into the cooling chamber formed by the pipes K and thence through the ports L past the non-return valve into the pipe L' and so into the cooling chamber G. In this chamber these products of combustion mingle with the compressed air contained therein and this mixture of cooled and compressed air and products of combustion subsequently passes into the cylinders A and A' to form part of the main charges therein. When the pressure in the cylinder B and in the cooling device K falls below that which exists in the cooling chamber G the valve between the chambers K and G closes and as the pressure continues to fall in the cylinder B there will be a tendency for the cooled products of combustion contained in the pipes K to flow back into the cylinder and pass away through the exhaust port when the valve M is lifted. The pressure in the cooling chamber K will thus have fallen to such an extent that there will be no tendency for the residual products of combustion in the pipes K to pass into the cylinder B on the pump side of the piston D when the latter is making its instroke and has uncovered the ports B' on the pump side of the piston. The pump end of the cylinder B is then filled with air which has been drawn in by the pump action of the instroke of the piston D. Yet, further, as the piston D on its outstroke compresses this air there will, in effect, be no tendency for this air to pass through the cooling chamber K owing to the fact that the pressure in the pump end of the cylinder B will not have risen sufficiently to lift the non-return valve controlling the ports L before the ports B' are covered by the piston on its outstroke. In other words up to the time that the ports B' are covered and communication between the pump side of the piston D and the cooling device K is shut off the pressure in the pump end of the cylinder B will tend to be lower than that which exists in the cooling device G.
- The non-return valve controlling the ports or passages L is of the spring-leaf type which can be used without risk of it being burnt out since the products of combustion are subjected to a preliminary cooling as they pass through the pipes K and before they reach this valve.
- In the alternative arrangement illustrated in Fig. 2 in place of the ports B' in the length of the wall of the cylinder B a port B² is formed in the head of the cylinder and controlled by a valve N suitably operated. From this port B² runs a passage or pipe which leads to the ends of the group of cooling tubes K. In this case where the products of combustion pass through a valve controlled port, this port need not necessarily be formed in the low pressure cylinder but may be in one or both of the high pressure cylinders as may be found most convenient. If the valve N controlling this port is opened after the valve controlling the passage between the high pressure cylinder and the low pressure cylinder has been lifted the gas pressure in these two cylinders is equal and hence it is immaterial from which cylinder the gases are drawn to pass to the cooling chamber. With this construction the passage of the products of combustion from the cylinder B into a cooling device K can be accurately timed to take place at such a point in the outstroke of the piston D as may be desirable. Owing to the provision of the valve N it is not necessary in this construction to provide a non-return valve at the other end of the cooling tubes K where they lead into the pipe L'.
- What I claim as my invention and desire to secure by Letters Patent is:—
1. In a compound internal combustion engine the combination of two high pressure cylinders, a low pressure cylinder, means for conveying a portion of the products of combustion from the low pressure cylinder to each high pressure cylinder in turn wherein these gases form part of the main charge, and means for cooling these products of combustion after they leave the low pressure cylinder and before they enter a high pressure cylinder as set forth. 105
  2. In a compound internal combustion engine the combination of two high pressure cylinders, means for delivering gases under pressure to these cylinders, a low pressure cylinder, means for conveying part of the products of combustion from the low pressure cylinder to each high pressure cylinder in turn wherein these gases form part of the main charge, and means for cooling these products of combustion after they leave the low pressure cylinder and before they enter a high pressure cylinder as set forth. 110
  3. In a compound internal combustion engine the combination of two high pressure cylinders, means for compressing the gases constituting the main charges before these gases are admitted to the high pressure cylinders wherein these gases undergo further 120

and the main cooled chamber, a non-return valve in this passage, and means for conveying the compressed and cooled gases from the main cooled chamber to the high pressure cylinders wherein these gases form a part of the main charge as set forth.

11. In a compound internal combustion engine the combination of two high pressure cylinders, a valve controlled inlet port in the head of each high pressure cylinder, means for imparting preliminary compression to the gases which are to constitute the main charges in the high pressure cylinders, means for delivering a lesser proportion of these gases after such preliminary compression directly to the high pressure cylinders, a cooled chamber into which pass the larger proportion of these gases after such preliminary compression, a low pressure cylinder, a cooled chamber in such communication with the low pressure cylinder that products of combustion can pass from the low pressure cylinder into this chamber wherein these gases receive preliminary cooling, a communicating passage between this preliminary cooling chamber and the main cooled chamber, and means for conveying the compressed and cooled gases from the main cooled chamber to the valve-controlled inlet ports in the high pressure cylinders wherein these gases form a part of the main charge as set forth.

12. In a compound internal combustion engine the combination of two high pressure cylinders, a valve-controlled inlet port in the head of each high pressure cylinder, means for imparting preliminary compression to the gases which are to constitute the main charges in the high pressure cylinders, means for delivering a lesser proportion of these gases after such preliminary compression directly to the high pressure cylinders, a cooled chamber into which pass the larger proportion of these gases after such preliminary compression, a low pressure cylinder, a cooled chamber in such communication with the low pressure cylinder that products of combustion can pass from the low pressure cylinder into this chamber wherein these gases receive preliminary cooling, a communicating passage between this preliminary cooling chamber and the main cooled chamber, a non-return valve in this passage, and means for conveying the compressed and cooled gases from the main cooled chamber to the valve-controlled inlet ports in the high pressure cylinders wherein these gases form a part of the main charge as set forth.

13. In a compound internal combustion engine the combination of two high pressure cylinders, means for imparting preliminary compression to the gases which are to constitute the main charges in the high pressure cylinders, means for delivering a lesser proportion of these gases after such preliminary

compression directly to the high pressure cylinders, a cooled chamber into which pass the larger proportion of these gases after such preliminary compression, a low pressure cylinder, a piston in this cylinder, ports in the wall of this low pressure cylinder positioned where they will be uncovered by the piston after it has performed one half of its outstroke, a cooled chamber in such communication with the piston controlled ports in the wall of the low pressure cylinder that products of combustion can pass from this cylinder into this chamber wherein these gases receive preliminary cooling, a communicating passage between this preliminary cooling chamber and the main cooled chamber, a non-return valve in this passage, and means for conveying the compressed and cooled gases from the main cooled chamber to the high pressure cylinders wherein these gases form a part of the main charge as set forth.

14. In a compound internal combustion engine the combination of two high pressure cylinders, a valve-controlled port in the head of each high pressure cylinder, means for imparting preliminary compression to the gases which are to constitute the main charges in the high pressure cylinders, means for delivering a lesser proportion of these gases after such preliminary compression directly to the high pressure cylinders, a cooled chamber into which pass the larger proportion of these gases after such preliminary compression, a low pressure cylinder, a piston in this cylinder, ports in the wall of the low pressure cylinder positioned where they will be uncovered by the piston after it has performed one half of its outstroke, a cooled chamber in such communication with the piston controlled ports in the wall of the low pressure cylinder that products of combustion can pass from this cylinder into this chamber wherein these gases receive preliminary cooling, a communicating passage between this preliminary cooling chamber and the main cooled chamber, a non-return valve in this passage, and means for conveying the compressed and cooled gases from the main cooled chamber to the valve-controlled inlet ports in the high pressure cylinders wherein these gases form a part of the main charge as set forth.

15. In a compound internal combustion engine the combination of two high pressure cylinders each formed with a pump chamber at one end, a valve-controlled port in the head of each high pressure cylinder, a differential piston in each high pressure cylinder operative to compress gaseous charges in the pump chamber end of that cylinder, means for conveying successive gaseous charges from these pump chambers to the combustion chambers of the high pressure cylinders wherein these charges form part

ot the main charges and as such are further compressed in these cylinders, a low pressure cylinder formed with a pump chamber at one end thereof, a differential piston in this 5 low pressure cylinder operative to compress gaseous charges in the pump chamber end of this cylinder, ports in the wall of the low pressure cylinder positioned where they will be uncovered by the piston after it has per-
10 formed one half of its outstroke, a cooled chamber into which pass the compressed gaseous charges from the pump chamber end of the low pressure cylinder, a cooled chamber in such communication with the piston controlled ports in the wall of the low pres-
15 sure cylinder that products of combustion can pass from this cylinder into this cham-

ber wherein these gases receive preliminary cooling, a communicating passage between this preliminary cooling chamber and the 20 main cooled chamber, a non-return valve in this passage, and means for conveying the compressed and cooled gases from the main cooled chamber to the valve-controlled inlet ports in the high pressure cylinders wherein 25 these gases form a part of the main charge as set forth.

In testimony whereof I have signed my name to this specification in the presence of two subscribing witnesses:
